UNITED STATES PATENT OFFICE.

CHARLES R. APPLEBY, OF BOLIVAR, NEW YORK.

POWER WINCH FOR TRACTORS.

Application filed March 16, 1927. Serial No. 175,791.

This invention relates to new and useful improvements in power winches for tractors especially adaptable for use in the drilling of oil, gas, and artesian wells as well as for the pulling of rods, and tubing from a well, the bailing of the same and other such purposes.

The primary object of the invention resides in the provision of a winch of this character that is so constructed as to permit of its association upon the forward end of a conventional tractor, and to receive its power from the power take off shaft of the tractor.

A further and important object resides in the provision of a winch of this character that includes a cable drum together with means for causing the quick change of rotation of the drum from one direction to another, and this through the medium of a single operating lever.

A still further and important object is to provide a winch of this character that may be associated with conventional designs of tractors without in any manner whatever altering the construction of such tractors.

With the foregoing and other objects in view as the nature of the invention will be better understood, the same comprises the novel form, combination and arrangement of parts hereinafter more fully described, shown in the accompanying drawings and claimed.

In the drawings wherein like numerals of reference indicate corresponding parts throughout the several views:

Figure 1 is a fragmentary side elevation of the front end of a conventional tractor equipped with my improved winch construction.

Figure 2 is a top plan view thereof.

Figure 3 is a front end elevation.

Figure 4 is an enlarged detail section taken in back of the cable drum of the winch for more clearly disclosing the means whereby the rotation of the drum may be rapidly reversed for causing the quick winding or unwinding of the cable with respect to said drum, and

Figure 5 is a fragmentary section of a modified form of drive means between said cable drum and the tractor operated shaft of the present winch device.

Now having particular reference to the drawings, A designates fragmentarily a conventional design of tractor that includes the usual side frame bars B—B between the for-

ward ends of which is supported the usual motor C having the usual power take off shaft D.

In carrying out my invention there is rigidly secured to the forward ends of the tractor frame bars B—B a pair of horizontally arranged extension bars 5—5, preferably interconnected at their forward ends by cross bar 6. Journaled within suitable bearings 7—7 upon the bars 5—5 adjacent the rear ends thereof is a transverse shaft 8, the outer end of which is equipped with a sprocket gear 9 over which is trained an endless chain 10 that extends rearwardly and is in turn trained over a sprocket gear 11 upon the end of said tractor power take off shaft D, see Figures 1 and 2.

Arranged upon this shaft 8 inwardly of the bar 5 adjacent the sprocket gear 9 is a generally conventional inside friction clutch unit 12 which in the present instance includes a spur gear 13 loose upon the shaft 8 together with a friction clutch member 14 splined upon the said shaft 8 and adapted for engagement with the rim of the gear for locking or releasing the same with respect to said shaft 8.

Splined upon the shaft 8 at the opposite end thereof is a beveled friction gear 15 equipped at its inner face with a collar 16.

Arranged transversely beneath the extension bars 5—5 attached to the tractor frame bars B—B and at a point below the shaft 8 is a cross strap 17 to which are pivoted the lower ends of a pair of upwardly extending levers 18—18 equipped intermediate their ends with yokes 19—19 for association with the movable clutch member 14 of the clutch unit 12 and with the collar 16 of the bevel friction gear 15, respectively. The upper end of the lever 18 adjacent the friction gear 15 is formed with a plurality of spaced openings 20 so as to permit of the adjustable pivotal connection of a link 21 thereto, the opposite end of the link being in turn formed with spaced openings 22 so as to permit of its adjustable pivotal connection with the upper end of the other lever 18 which terminates slightly short of the upper end of the first mentioned lever as disclosed in Figure 4. Pivoted to the upper end of the lever 18 adjacent the friction gear 15 is a laterally extending rod 23 that is pivoted to the adjacent arm of a bell crank 24 that is in turn piv-

100

105

oted to the upper end of a vertical strap 25 secured at its lower end to the adjacent bar 5 of the winch frame structure.

As clearly disclosed in Figure 2 the outer 5 arm of the bell crank serves as a lever for swinging the levers 18—18 upon their pivots for controlling the movement of the movable clutch member 14 of the clutch unit 12, and the splined friction gear 15 in similar directions 10 upon the shaft 8.

Journaled within a pair of transversely aligned bearings 26—26 upon the top sides of the extension bars 5—5 forwardly of the bearing 7—7 is a shaft 27 keyed to which is 15 a cable drum 28. The end of this cable drum adjacent the sprocket gear 9 is equipped with a large sprocket gear 29 over which is trained an endless chain 30 that is extended rearwardly and thence turned over the sprocket 20 gear 13 so that a rotation of this gear will cause the rotation of the drum 28 in one direction. Upon the inner end of this drum is a large beveled friction gear 31 complementary to the bevel friction gear 15 of the 25 shaft 8, and adapted to be engaged by this gear 15 when the bell crank lever 24 is so operated as to cut out the operation of the gear 13 of the clutch 12 for causing the rotation of the drum 28 in a reverse direction.

30 In Figure 5 a slightly modified form of driving mechanism is provided between the inner end of the shaft 8 and the drum shaft 27. In this instance the inner end of said drum 28' is equipped with a gear 31', while 35 upon the power operated shaft which in this view is designated 8' there is splined a small gear 15'. This gear 15' is constructed for operable association with the innermost vertical lever 18 so that when said lever is operated 40 simultaneously with the operation of the adjacent lever, said gear 15' will be moved into or out of engagement with the gear 31' of the drum 28'.

It will thus be seen that I have provided 45 a highly novel, simple, and inexpensive power winch for association with conventional types of tractors that is well adapted for all the purposes heretofore designated and even though I have herein shown and de-

scribed the invention as consisting of certain detail structural elements it is nevertheless to be understood that some changes may be made therein without affecting the spirit and scope of the appended claim.

Having thus described the invention, what 55 I claim is:—

In a power winch for tractors, a pair of longitudinally extending spaced frame bars rigidly secured to the forward end of the tractor, a U-shaped bar connecting at its ends to the respective frame bars and at the bottom sides thereof, the main power shaft journaled transversely of said frame bars, a driving connection between the shaft and the power take-off shaft of the tractor, a clutch upon said shaft including an internal clutch member having a sprocket upon its outer face and loose upon the shaft, and a clutch member splined upon the shaft and constructed for engagement with the first clutch member to cause the locking of said members to said shaft, a gear splined upon said shaft adjacent its opposite end, a shaft journaled upon said bars forwardly of the first-mentioned shaft, the cable drum operatively associated with said shaft, a sprocket upon one end of the drum in alinement with the sprocket upon the first-mentioned shaft, a chain connection between said sprockets, a gear upon the opposite end of the drum, and single means for causing the actuation of the movable member of the clutch and said gear upon the first mentioned shaft, whereby by the drum may be rotated in reverse directions, said means consisting of a pair of levers having their lower ends pivotally connected in the U-shaped member, and in spaced relation to each other, one of said levers being operatively connected to the splined clutch member, the opposite lever being operatively connected to the gear, said levers being connected at their upper ends, and a single throw lever operatively associated with one of said levers to cause the simultaneous parallel movement of the levers, when said throw lever is actuated.

In testimony whereof I affix my signature
CHARLES R. APPLEBY.
